UNITED STATES PATENT OFFICE

HENRY R. MINOR, OF OSSINING, NEW YORK, ASSIGNOR, BY MESNE ASSIGNMENTS, TO
WALTER KIDDE & COMPANY, INC., OF NEW YORK, N. Y., A CORPORATION OF NEW
YORK

FIRE EXTINGUISHER

Application filed September 26, 1925. Serial No. 58,736.

This invention relates to carbon dioxide fire extinguishers, and has for its object the production of a simple and efficient construction whereby liquid carbon dioxide is utilized as the source of carbon dioxide gas and snow for extinguishing fires.

Another object includes the provision of means whereby the entrainment of air is prevented and carbon dioxide is applied directly to the fire with remarkable results and great effectiveness. A further object includes the production of a carbon dioxide fire extinguisher which is light in weight and therefore readily and quickly transported, and whereof the maintenance cost is exceedingly low. I further provide a fire extinguishing medium which is penetrating, non-conducting and of low temperature. My fire extinguishing medium is very valuable for extinguishing fires in unusual or inaccessible places, and being a non-conductor at low temperatures, it is also valuable and very efficient for quenching electrical fires. It is also valuable and very efficient for extinguishing solvent fires where such solvent is composed of volatile materials, such as benzine, gasoline, etc.

I obtain these and other objects by the construction illustrated in the accompanying drawing, in which

Fig. 1 is a view in elevation and partly in cross section of a construction which embodies the principles of my invention.

Fig. 2 is a view in perspective of a carbon dioxide discharge nozzle, and its gas protecting and gas directing nozzle.

Fig. 3 is a sectional view of a carbon dioxide discharge nozzle.

Fig. 4 is a sectional view of the valve and

Fig. 5 is a sectional view of the end of the siphon tube in the cylinder.

Like numerals refer to similar parts throughout the several views.

The value of carbon dioxide gas and snow as a fire extinguishing medium has been known for a long time, and many attempts have been made to apply the gas in the most efficient manner. In this connection, particular effort has been directed towards the quenching of fires with carbon dioxide where special hazards exist, as in dry cleaning estab-

lishments, in chemical laboratories, in the oil or rubber industries, and other similar highly inflammable industries or storage places.

I have discovered that if the entrainment of air therewith can be prevented, carbon dioxide gas becomes one of the most efficient fire extinguishing mediums known, and the idea as conceived by me, and embodied in a practical application includes means whereby the gas is discharged within a protecting shield or device which surrounds the gas which is to be applied to the fire. Such a protecting shield or device not only prevents the entrainment of air along with the quenching gas, but has, in addition, also a secondary effect of great importance on the gas discharge as will be hereinafter explained.

Practical tests carried out by me with air restricting means for preventing the entrainment of air, proved the efficiency of carbon dioxide as a fire extinguishing medium. In this instance, the medium was applied directly to encase or blanket the combustible material to thus completely prevent combustion in a most surprising manner. Any suitable means for preventing the inrushing of the surrounding air will answer the purpose. One difficulty encountered in carrying out my practical tests where a nozzle in addition to the cone was employed has been that where liquid carbon dioxide is employed as a fire extinguishing medium there is a tendency of the great degree of cold caused by the release of the liquid and the resultant expansion of the same at the instant of release into gaseous form, to cause the chilling to a very low temperature of the nozzle or other means employed for delivery of the liquid to the point where it is released. This tendency is created when the expanding medium at or after the instant of release is permitted to come in close contact with the exterior surface of the nozzle or of the device employed, with the result that the column of liquid in the nozzle is extracted of its heat causing such column to freeze up within the nozzle and choke the bore thereof. The best results as a fire quenching medium, as I have found, are obtained when the liquid carbon dioxide is released and permitted to expand into gaseous form which

produces snow, so that the gas is applied to the fire mainly in the form of a finely divided CO₂ snow at a temperature of approximately 110° below zero so that certain advantages which are obtained consist in a higher specific gravity from the use of CO₂ snow rather than CO₂ gas, also the cooling effect available is of material help. I find an open ended vessel or hood having walls of preferably non-combustible material most satisfactory. As a practical embodiment of my invention for applying carbon dioxide, I have shown a cone-shaped vessel 10, or an equivalent rectangular vessel 11. The cone-shaped vessel 15 or shield is of substantial length, that is, of such length that fluids leaving its flared end are, due to gradually increasing diameter of the shield, reduced in their velocity so that they entrain substantially no air. The vessels are provided with an open mouth 12 and have one or more carbon dioxide supplying nozzles 13 (or 13') enclosed therein. These nozzles are connected by a flexible metal hose 14 to a quick release valve 15 on a cylinder 16 of desired dimensions. This cylinder is designed for holding the liquefied carbon dioxide as the source for the gas and it is normally about two-thirds full of liquid. A siphon tube 17 extends from the valve into the gas 30 to near the bottom of the cylinder. At the lower end of this tube a recess 18 is provided to equalize the feed.

The cone or nozzle is shown, in this instance, as being exteriorly tapered toward its 35 base and away from the line of discharge of the gas through the bore thereof, and is provided with a threaded nipple 20 for attachment to a connection tube 21. The cone or nozzle is also provided with a convenient nut 40 22, and a longitudinal bore having a sharp aperture 23 of restricted area, for the discharge of the gas. If desired, the bore of the cone or nozzle may be of gradually constricting area towards the discharge aperture 23. 45 In the operation of the device the gas, when released from its pressure by its discharge from the orifice 23, rapidly expands, and in its expansion absorbs heat from its surroundings. Since, however, the expanding gas, by 50 a structure and arrangement of cone or nozzle, of the character described, discharges with the least possible contact with the exterior surface of the nozzle or cone, it does not extract or absorb heat from the body of the 55 nozzle or cone and, hence, from the column of the liquid or other form of the gas contained in the bore of the cone, which, otherwise, might cause such column of liquid 60 or gas to freeze up within the cone or nozzle bore. It is the feature of reducing actual contact of the expanding gas with the exterior surface of the cone or nozzle to the least possible point, that contributes to this 65 important feature and characteristic of my

invention, in whatever physical way this reduction of contact may be secured.

The cylinder is provided with a handle 25, and is adapted for easy transportation. The apparatus is light in weight in comparison with the amount of gas used, as one volume of gas compressed in a cylinder is equal to about 450 volumes at atmospheric pressure. The use of the siphon tube has the advantage of delivering the gas at a uniform pressure 70 without undue ebullition, and there is no great tendency to freeze, due to the absorption of heat. The purpose of the siphon tube is to remove the liquid portion of the gas first as CO₂ snow is made only from the liquid portion and it is obvious that if there was no siphon tube only gas would be drawn off as the liquid would boil as the reduction in the pressure was accomplished. The apparatus is always ready for quick service and when needed, the quick relief valve 15 is opened and the gas is directed by the hood towards the flame which is choked thereby. The heavier than air carbon dioxide gas and snow affords a very effective means of extinguishing concealed flames or embers in inaccessible places.

While I have disclosed a specific embodiment I do not desire to be understood thereby as having limited myself unduly, as various forms falling wholly within the spirit and scope of my invention will present themselves to those versed in the art.

What I claim therefore, as new and useful, of my own invention and desire to secure by Letters Patent, is:

1. The method of extinguishing fire which comprises projecting a jet of fire extinguishing gas at a high velocity and interposing in close contiguity to said jet a protective shield between the jet and the laterally adjacent atmospheric air so long as the velocity of said jet is otherwise sufficient to entrain air.

2. In a fire extinguishing apparatus employing a liquid which in use is converted into gaseous and solid form and which is most effective as a fire extinguishing medium when free of air, the combination including a container of the liquid, a nozzle having a restricted discharge orifice and in free communication with the container for discharging the liquid and an outwardly flaring shield completely enclosing at its smaller end said nozzle into which the nozzle discharges, said shield being of such length that the discharge 110 when issuing from the shield no longer has sufficient velocity to entrain substantially any air.

3. In a fire extinguishing apparatus employing liquid carbon dioxide discharged without entrainment of air, the combination comprising a container of liquid carbon dioxide, a nozzle having a restricted discharge orifice and in free communication with said container so that liquid carbon 125

dioxide only is delivered to the mouth of the nozzle and discharged therefrom, and an outwardly flaring shield of substantial length, which shield completely encloses at its smaller 5 end the nozzle and surrounds the discharge from the nozzle.

In testimony whereof, I have hereunto set my hand on this first day of September A. D., 1925.
